SYSTEM FOR HEATING LIQUIDS

Vernon F. Parry, Golden, Colo., assignor to the
United States of America, as represented by the
Secretary of the Interior

Application November 7, 1945, Serial No. 627,274

3 Claims. (Cl. 122—15)

(Granted under the act of March 3, 1883, as
amended April 30, 1928; 370 O. G. 757)

1

The invention described herein may be manufactured and used by or for the Government of the United States for governmental purposes without the payment to me of any royalty thereon in accordance with the provisions of the act of April 30, 1928 (ch. 460, 45 Stat. L. 467).

My invention relates to a system for heating liquids and particularly to one in combination with a coal stoker which preheats water with heat which would otherwise be wasted by conduction through the walls of a flue.

In the accompanying drawings illustrating one embodiment of my invention:

The single figure represents a vertical partial section which diagrammatically illustrates the operation of my system.

A closed base 11 is provided with an airtight cleanout closure, not shown, and supports a combustion dome 12 provided with a water jacket 13 and a discharge duct 14 for hot products of combustion. The jacket 13 is connected with a water heating coil 15 within a combustion flue 16 of a water jacket 17 which is provided with a heat conserving insulating jacket 18. A water supply pipe 19 extends downwardly through the water jacket 17 into which water is discharged from this pipe near the bottom of this jacket. The cooled products of combustion are discharged through a stack 20 and hot water may be drawn through a hot water discharge pipe 21, 22.

A water storage tank 23 is provided with a heat insulating jacket 24 and is supplied with pre-heated water from the top of the water jacket 17 through a pipe 25 which extends downwardly through the tank 23 to discharge water near the bottom of the tank. The discharge pipe 22 has a by-pass circulating pipe 26, which provides for a return circulation of water through the tank 23 whenever the temperature of water in the storage tank falls below a predetermined maximum temperature and no water is being drawn through the pipe 22. A manually-operated blow-off valve 27 provides for the removal of sediment from the storage tank 23 and a second blow-off valve 28 likewise provides for the removal of sediment from the water jacket 17.

A heat responsive switch 29 is mounted upon and near the top of the tank 23 is connected by an electric circuit 30 with an electric motor 31 which operates an automatic fuel stoker 32 which delivers granular fuel to a stoker retort 33 from which ashes overflow into an ash can 34 which can be withdrawn for emptying through the clean-out closure.

The period or interval of operation of the heat responsive switch 29, when no water is being drawn from the system, is governed by the rate of heat losses from water storage tank 23, and the thickness of the insulation jacket 24 is adjusted to produce the desired interval. When 60

2

burning low-rank fuels the interval between operations is in the range of 50 to 300 minutes, the interval decreasing as the rank of the fuel increases. The sensitivity, or range of operation of the heat responsive switch 29 is also adjusted to suit the properties of the fuel being burned, and by combination with insulating jacket 24 can be adjusted such that the interval between operations is 10 to 50 minutes. Thus an effect or control is attained which employs rate of heat losses to govern the period of firing and it eliminates the need for a mechanically operated time-o-stat. My system will therefore remain operative when consuming no power whatsoever for about 80 percent of the time, and economy, as well as higher efficiency is attained.

My system is designed for efficient utilization of the heat units of the consumed fuel, and particularly for preheating in the water jacket 17 the water with heat which would otherwise be wasted as well as for maintaining water in the storage tank 23.

I have shown and described one embodiment of my invention, but it is to be understood that it is capable of many modifications. Changes, therefore, in the construction and arrangement may be made without departing from the spirit and scope of the invention, as disclosed in the appended claims, in which it is my intention to claim all the novelty inherent therein as broadly as possible in view of the prior art.

What I claim is:

1. A water heating system comprising a water jacketed combustion dome provided with a discharge duct, a water heating coil operatively connected with said dome, a water jacket provided with a flue for products of combustion surrounding said coil, means for admitting water from an external source to said water jacket, a hot water discharge pipe coupled to said coil, a water storage tank operatively connected to the top of said water jacket, means connecting said storage tank with said water jacketed dome, heat-responsive switch mounted on said storage tank to be operated by fluctuations in the temperature of water in said storage tank, and an electric motor of an automatic fuel stoker electrically connected with said switch.

2. A water heating system comprising a water jacketed combustion dome provided with a discharge duct, a water heating coil operatively connected with said dome, a water jacket provided with a flue for products of combustion surrounding said coil, an external heat insulating jacket for said water jacket, a water supply pipe in said water jacket discharging near the bottom of the jacket, a heated water discharge pipe coupled to said coil, a heat insulated hot water storage tank, a pipe from the top of said water jacket extending downwardly through said storage tank, a

pipe connecting said storage tank with said dome, a circulating pipe connecting the top of said storage tank with said water discharge pipe, a heat responsive switch mounted on said storage tank adapted to close an electric circuit whenever the temperature of the water in the storage tank falls below a predetermined minimum and to break the circuit at a predetermined maximum temperature, and an electric motor adapted to be operated only when said heat responsive switch maintains a closed electric circuit to said motor, and an automatic fuel stoker operated by said motor.

3. A water heating system comprising a water jacketed combustion dome provided with a discharge duct for products of combustion, a water heating coil operatively connected with said dome and to a heated water discharge pipe, a water jacket provided with a flue for products of combustion surrounding said coil, an external heat insulating jacket for said water jacket, a water

supply pipe in said water jacket discharging near the bottom of the jacket, a preheated water discharge pipe leading from the top of the water jacket and discharging near the bottom of a storage tank, a heat insulated water storage tank, a draw-off pipe from the top of said water storage tank connected in circuit with said heated water discharge pipe through said coil and said water jacketed combustion dome and thence through a pipe to the base of the storage tank, a heat responsive switch mounted on said storage tank adapted to close an electric circuit whenever the temperature of the water in the storage tank falls below a predetermined minimum and to break the circuit at a predetermined maximum temperature, and an electric motor adapted to be operated only when said heat responsive switch maintains a closed circuit to said motor, and an automatic fuel stoker operated by said motor.

VERNON F. PARRY.
